Des. 219,819
Patented Feb. 2, 1971

219,819

MASONIC ORNAMENT

George M. Wallace, 64 Clinton St., Paterson, N.J. 07501

Filed July 1, 1969, Ser. No. 18,036

Term of patent 14 years

Int. Cl. D11—02

U.S. Cl. D29—23

FIG. 1 is a front elevational view of a masonic ornament showing my new design, the side opposite being similar thereto;

FIG. 2 is a side elevational view thereof; and

FIG. 3 is a top plan view with the top portion in cross section at the base.

I claim:

The ornamental design for a masonic ornament, substantially as shown.
